UNITED STATES PATENT OFFICE.

DAVID FEIGENBAUM, OF BROOKLYN, NEW YORK.

COLLAR SUPPORT.

1,414,119.

Specification of Letters Patent. Patented Apr. 25, 1922.

Application filed August 20, 1920. Serial No. 404,723.

To all whom it may concern:

Be it known that I, DAVID FEIGENBAUM, a citizen of the United States, and a resident of the city of New York, borough of Brooklyn, county of Kings, and State of New York, have invented a new and Improved Collar Support, of which the following is a full, clear, and exact description.

This invention relates to a supporting device for collars and has for an object to provide an improved construction wherein a soft collar is properly supported without disturbing the usual appearance of the collar.

Another object of the invention is to provide a support for a soft collar wherein a removable stiffening device is provided adjacent the front of the collar for preventing crumpling of the collar.

A still further object of the invention is to provide a support for a soft collar which will support both the inner and outer part of the collar and present a supporting ridge to the edge of the collar near the front.

In the accompanying drawing—

Figure 1 is a perspective view of a soft collar shown applied on a shirt with an embodiment of the invention shown in dotted lines applied thereto.

Figure 2 is a fragmentary perspective view of one end of the collar shown in Figure 1 and illustrating how the invention is applied and the position assumed when the collar is spread.

Figure 3 is a plan view of the supporting member removed.

Figure 4 is a view similar to Figure 2 but showing a modified form of the invention.

Figure 5 is a plan view of the stiffening member shown in Figure 4.

Referring to the drawing by numerals 1 indicates a shirt of any desired kind provided with the usual neck band 2 for receiving the collar 3, which collar is an ordinary soft collar provided with a neck band section 4 and an outside or ornamental section 5. This form of collar is old and well known and is being more and more widely used as the comfort from such a soft collar is very desirable. In many instances, however, especially in hot weather, the collar will become moist and crumpled so that it will present an undesirable appearance. To avoid this crumpling of the collar when used for some length of time a supporting member 6 is provided which is formed with a body 7 having supporting arms 8 and 9 extending from one edge thereof. This supporting

member may be made from celluloid, rubber or other desired material, said material being preferably flexible. In order that the support 6 may be properly held in position as indicated by dotted lines in Figure 1, pockets 10 and 11 are secured to the section 4 and section 5. The pocket 10 secured to section 5 is preferably connected therewith adjacent the ends of the pocket so that a necktie 12 may be inserted beneath the pocket and held in correct position thereby.

The arm 8 is designed to be longer than arm 9 as it is inserted in pocket 10 which is at the front and deeper part of section 5, while the arm 9 is inserted into pocket 11 carried by the neck band section 4 of the collar. In this way, both sections of the collar are stiffened and supported though the stiffening is flexible and will allow the collar to flex in a natural manner but will hold the same in an upright position unless positively forced from such position.

In addition to acting as stiffening members for the two sections of the collar the body 7 is arranged so that the upper edge will engage the folded edge 13 of the collar and act as a support therefor, said body extending for any desired distance toward the rear. Preferably there are two supporting members 6 for each collar and by reason of the arrangement of the body 7, the edge 13 on each side of the front of the collar is properly supported notwithstanding any perspiration that might be deposited thereon.

The support 6 and the pockets 10 and 11 will not prevent soiling of the collar but will hold the collar in its usual correct position without presenting a stiff structure as is present in an ordinary starched collar.

In some instances it might be desired to merely provide a small amount of stiffening to the front section 5 of the collar and when this is the case a pocket 14 is provided which is preferably stitched to the collar at 15 and connected at the opposite end by suitable button 16 though stitching could be substituted if desired. A single slab or strip 17 of celluloid or other resilient stiffening material is removably positioned in the pocket 14 whereby the front part of the section 5 is properly supported and stiffened to a certain extent.

What I claim is:

1. In a collar of the character described, a pair of pockets arranged on the collar band and the folded over band of said collar, each of said pockets opening in the same direction

as the other and at a distance from each other, and a resilient stiffening member having a pair of legs adapted to fit in said pockets, and a body extending beyond said 5 legs adapted to lie parallel to the line of fold and under the folded over band of said collar.

2. A support for soft collars including a resilient body provided with a straight edge and a rounded end, a leg projecting from said body from a point short of said rounded end, and a second leg projecting parallel to the first from the other end of said body. 10

DAVID FEIGENBAUM.
